UNITED STATES PATENT OFFICE.

EBY R. APPLIN, OF WAUPUN, WISCONSIN.

STOCKING DRYING AND SHAPING FORM.

1,103,245.

Specification of Letters Patent. Patented July 14, 1914.

Application filed February 9, 1914. Serial No. 817,661.

To all whom it may concern

Be it known that I, EBY R. APPLIN, a citizen of the United States, and resident of city of Waupun, in the county of Dodge and State of Wisconsin, have invented certain new and useful Improvements in Stocking Drying and Shaping Forms; and I do hereby declare that the following is a full, clear, and exact description thereof.

10 My invention consists in what is herein particularly set forth with reference to the accompanying drawings and pointed out in the claims of this specification, its object being to provide simple, economical, efficient and practically non-expansible stocking drying and shaping forms for use in knitting factories, the construction of my improved forms being such as to prevent their collapse and to successfully resist pressure therein of steam or hot water employed as the heating medium.

Figure 1 of the drawings represents a side elevation of a stocking drying and shaping form in accordance with my invention in a stocking that is partly broken away; Fig. 2, a partly sectional elevation of a fragment of the form; Figs. 3 and 4, cross-sections illustrating steps in the manufacture of the form, and Fig. 5, a similar view of the completed form, this view being on the plane indicated by line 5—5 in Fig. 2.

Referring by numeral to the drawings, 6 indicates a shell of suitable sheet-metal constituting the lining of my improved form, said lining being elliptical or otherwise in cross-section. At intervals of its length the sides of the shell may be braced apart by means of a series of washers 7 therein forming a sleeve on a rivet 8 that is upset at its ends outside of said shell, or the sleeve may be a single piece.

The shell is outwardly reinforced by a wrapping 9 of suitable wire and, after being tinned, the product is centered in a suitable mold and cast in a coating 10 of block-tin or some suitable alloy, or a coating of vitreous enamel may be substituted for the metal coating or applied thereto, the coating being non-corrosive under ordinary conditions.

10 The leg end of the shell is brazed or other-

wise connected to a coupling 11 by which to connect it to a steam or hot water service pipe, the toe end of said form being closed. The general contour of the form longitudinally thereof is that shown in Fig. 1, and in 55 practice said form is employed toe-end up on a stand through which the pipe for steam or hot water extends, said stand being set upon a table or other suitable support.

I claim:

1. A stocking drying and shaping form consisting of a sheet-metal lining shell inwardly braced at intervals of its length against collapse, a wire-wrapping on the shell constituting an outer reinforce for the 65 same against internal pressure, and a coating of suitable material solidified on the wire-wrapped shell.

2. A stocking drying and shaping form consisting of a sheet-metal lining shell, 70 bracing sleeves therein at intervals of its length on rivets upset at their ends outside of the shell, a wire-wrapping on the shell constituting an outer reinforce for the same against internal pressure, and a coating of 75 suitable material solidified on the wire-wrapped shell.

3. A stocking drying and shaping form consisting of a sheet-metal lining shell inwardly braced at intervals of its length 80 against collapse, a wire-wrapping on the shell constituting an outer reinforce for the same against internal pressure, and a coating of block-tin molded on the wire-wrapped shell.

4. A stocking drying and shaping form consisting of a sheet-metal lining shell having an outer wrapping of wire constituting a reinforce against internal pressure, and a 90 coating of suitable material solidified on the wire-wrapped shell.

In testimony that I claim the foregoing I have hereunto set my hand at Waupun in the county of Dodge and State of Wisconsin in the presence of two witnesses.

EBY R. APPLIN.

Witnesses:

R. D. TILLOTSON,
S. J. DOWLING.
